SPECIFICATION forming part of Design No. 12,461, dated September 13, 1881.
Application filed August 9, 1881. Term of patent 3½ years.

To all whom it may concern:

Be it known that I, HENRY HORAN, of East Orange, in the county of Essex and State of New Jersey, have invented a new and original 5 Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

On the groundwork of the carpet are two 10 large bouquets, A and B, of leaves and flowers. 15 From the bouquet B projects a twig, C, up-

ward, and reaches to the lower end of bouquet A. Another twig, D, projects downward from the bouquet B, nearly reaching contact with the upper part of figure A.

I claim—

1. The design for carpets, consisting of the figure A, substantially as shown.
2. The design for carpets, consisting of the figure B, substantially as shown.
3. The design for carpets, consisting of the figures A B C D, substantially as shown.

HENRY HORAN.
